UNITED STATES PATENT OFFICE.

WILLIAM J. HAYNES, JR., OF KANSAS CITY, MISSOURI.

DESIGN FOR A FURNACE.

59,220.

Specification for Design.

Patented Oct. 4, 1921.

Application filed July 29, 1920. Serial No. 399,908. Term of patent 14 years.

To all whom it may concern:

Be it known that I, WILLIAM J. HAYNES, Jr., a citizen of the United States, residing at Kansas City, in the county of Jackson and State of Missouri, have invented a new, original, and ornamental Design for Furnaces, of which the following is a specification, reference being had to the accompanying drawing, forming part thereof.

Figures 1 and 2 are respectively perspective and plan views of my new design for a furnace.

I claim—

The ornamental design for a furnace, as shown.

WILLIAM J. HAYNES, JUNIOR.
